UNITED STATES PATENT OFFICE.

HARRY M. PFLAGER, OF ST. LOUIS, MISSOURI

CAR CONSTRUCTION.

1,101,955.

Specification of Letters Patent. Patented June 30, 1914.

Application filed February 21, 1914. Serial No. 820,184.

To all whom it may concern:

Be it known that I, HARRY M. PFLAGER, a citizen of the United States, residing at the city of St. Louis, State of Missouri, have invented a certain new and useful Improvement in Car Construction, of which the following is a full, clear, and exact description, such as will enable others skilled in the art to which it appertains to make and use the same, reference being had to the accompanying drawings, forming part of this specification, in which—

Figure 1 is a partial top plan view of my improvement in car construction. Fig. 2 is a side elevational view partly in section. Fig. 3 is a vertical transverse sectional view. Fig. 4 is an end elevational view. Fig. 5 is a horizontal sectional view through the journal box and pedestal.

This invention relates to a new and useful improvement in car construction of that type disclosed in United States Letters Patent No. 999,253 granted to me August 1, 1911.

My present invention is intended to produce a truck side frame which is flexible so as to render the car "easy riding".

In the drawings 1 indicates the body bolster under each end of which is secured a casting 2, said casting having pedestal jaws 3 depending therefrom and arranged in pairs at each end of said casting, said pedestal jaws being provided with openings or slots in their inner vertical walls to receive guiding projections 4 extending from the journal boxes 5 in which are mounted axles 6 carrying the wheels 7. The journal boxes will thus have independent vertical movement in their pedestals, said journal boxes supporting an equalizing bar 8 on which is arranged a concave bearing 9.

10 indicates a spring follower having a spherical bearing on its under side seated in the equalizer bearing 9, there being springs 45 11 interposed between the spring follower 10 and the upper wall of the casting 2. Casting 2 forms a housing for the springs to prevent their accidental displacement, said springs likewise being centered by teats such 50 as are commonly employed in truck construction. The outer pedestal jaws 12 are preferably in the form of castings so as to permit easy introduction and removal of the journal boxes, the extremities of all of said

pedestal jaws being held together by the tie 55 bar 13.

By the above construction, it will be noted that the equalizer bar permits independent vertical movement of the axle boxes, the rocking bearing permitting this movement. 60 The ends of the equalizing bar preferably have an extended flat bearing surface which cooperates with the journal boxes for the purpose of normally maintaining the journal boxes in the same horizontal plane. 65 These bearing faces, however, permit any journal box to fall or rise independently of its companion passing over inequalities in the track.

It will be noted by reference to Fig. 5 that 70 the lugs on the sides of the journal boxes are narrower than the opening in the pedestals receiving them, thus permitting said journal boxes to have a movement in the pedestals in a direction longitudinal of the 75 axle.

While I have shown my improved truck side frame secured rigidly to the body bolster of the car, it is obvious that it could be secured to the side sills or other portions 80 of the car underframe and in the claims where this element is mentioned as being secured to the car underframe, it will be understood that such an expression means that the truck side frame is secured rigidly to the 85 car body or to some of the frame members thereof.

I claim:

1. In car construction, the combination of truck side frames rigidly secured to the car 90 underframing and having pedestal jaws, journal boxes guided vertically by said pedestal jaws, an equalizer bar having its end supported by said journal boxes, and springs interposed between said equalizer bar and 95 said car underframe.

2. In car construction, a truck side frame rigidly secured to the underframing of the car, journal boxes mounted for vertical movement in said side frame, an equalizer 100 bar having its ends cooperating with said journal boxes, said equalizer bar also carrying a seat, a spring follower bearing in said seat, and springs interposed between said follower and the car underframe.

3. In car construction, a truck side frame rigidly secured to the car underframe, journal boxes mounted for vertical movement in

said side frame, an equalizing bar having flat faces at each end coöperating with said journal boxes, and springs interposed between the equalizing bar and the underframe.

4. In car construction, the combination of pedestals rigidly secured to the car underframe, journal boxes guided vertically in said pedestals, an equalizer bar having its 10 end supported by said journal boxes, and springs interposed between said equalizer bar and said car underframe.

5. In car construction, an underframe,

pedestals rigidly secured to said underframe, journal boxes mounted for vertical and longitudinal movement in said pedestals, an equalizer bar having its ends bearing against the journal boxes, and springs interposed between the equalizer bar and the underframe.

In testimony whereof I hereunto affix my 15 signature in the presence of two witnesses, this 7th day of February, 1914.

HARRY M. PFLAGER.
